EXERCISING APPARATUS

Filed Sept. 1, 1928

UNITED STATES PATENT OFFICE

HEINRICH ZINNOW AND WILHELM SIEVERS, OF UTICA, NEW YORK

EXERCISING APPARATUS

Application filed September 1, 1928. Serial No. 303,402.

This invention relates to exercising devices and more particularly to means for mounting punching bags.

Exercise with a punching bag is designed 5 to train the eye of the person as well as the muscles of the body. Consequently, it is desirable that the bag be mounted so that it will follow no definite path in its movements. The usual ball and socket mounting for 10 punching bags gives a universal movement of the bag, but the movement is more or less along a definite path and the person using the bag soon becomes accustomed to the actions of the bag.

15 It is therefore an object of this invention to provide a mounting for a punching bag which will make the movements of the bag more or less indefinite, and as a result train the eye of a user more satisfactorily than with the usual 20 type of bag mounting.

It is a further object of the invention to provide a mounting which may be used with standard punching bags without material alteration of the bag.

25 These and other objects are attained by the novel construction, combination and arrangement of parts, hereinafter described and shown in the accompanying drawing, constituting a material part of this disclosure, and 30 in which:—

Figure 1 is an elevational view showing one method of mounting the bag.

Figure 2 is a cross-sectional view taken along the line 2—2 of Figure 1.

35 Figure 3 is an elevational view showing another method of mounting the bag.

Referring to the drawings, a vertical support 3 consisting, in this case, of a metal pipe, is rigidly held to a base 4 by means of braces 5.

40 At the upper end of this support, a collar 6 is clamped to the pipe by means of a set screw having a handle 7. The collar is provided with a hollow lateral extension 8 which supports a pipe 9, the other end of the pipe 45 being supported by a collar 10 similar to collar 6, the collar 10 being clamped to a short vertical pipe 11 by a set screw having a handle 12.

Fixed to the pipe 11 is a collar 13, abutting 50 one end of a coil spring 14, the other end of

the spring abutting the small end of a pear-shaped punching bag 15. The bag is supported by a cord 16 wound about a drum 17 journaled in the pipe 11 and manipulated by a handle 18.

With a bag mounted in the vertical position, as above described, it is obvious that the spring 14 prevents the bag from following a definite path when struck and causes the action of the bag to be uncertain, so that a person using the bag must be quick of eye and alert just as he would have to be were he engaged in a boxing contest with another person.

55 Mounted on the pipe 3 at about the height of the shoulders of an average man is a collar 19 which is adjustably clamped to the pipe by means of a set screw having a handle 20. The collar 19 is provided with a lateral hollow extension 21 and lower and upper hooks 22 and 23, to which are respectively attached springs 25 and 24, the springs being also attached at their opposite ends to a convolution of the coil spring 26. One end of the 60 spring 26 embraces the extension 21 and abuts the collar 19, while the other end of spring 26 abuts the small end of punching bag 27, which is also abutted by a tube 28, surrounding a portion of spring 26.

65 The bag 27 is held against the spring 26 and tube 28 by means of a cord 29 wound about a drum 30, the latter being journaled in the hollow extension 21 and manipulated by a handle 31.

70 This horizontally positioned bag 27 gives results similar to those obtained with the bag 15, that is, trains the eye of the user to quickly observe the uncertain movements of the bag. Springs 24 and 25 resiliently maintain the bag in a horizontal position, at the same time adding to the effect of spring 26.

75 From the above description, it will be seen that we have provided a highly desirable punching bag apparatus which is especially adapted for use by persons training for boxing contests, as the uncertain movements of the bags simulate the uncertain movements of a boxing opponent.

80 The foregoing disclosure is to be regarded as descriptive and illustrative only and not as 100

restrictive or limitative of the invention, of which obviously an embodiment may be constructed, including many modifications, without departing from the general scope herein indicated and denoted in the appended claim.

5 Having thus described our invention, what we claim as new and desire to secure by Letters Patent, is:—

10 A mounting for a punching bag, comprising a vertical tubular support, a collar having a lateral hollow extension, means to clamp the collar to the support, a pair of hooks on the collar, a coil spring surrounding the extension and abutting the collar at one end, 15 the other end of the spring abutting the small end of a punching bag, springs engaging the hooks and convolution of the coil spring, a cord fixed to the bag, and a drum about which the cord is wound, said drum being journaled 20 in the extension.

25 In witness whereof we have affixed our signatures.

HEINRICH ZINNOW.
WILHELM SIEVERS.
